UNITED STATES PATENT OFFICE.

FRANK MAYHEW, OF PHILADELPHIA, PENNSYLVANIA, ASSIGNOR TO ATLAS BALL COMPANY, OF PHILADELPHIA, PENNSYLVANIA, A CORPORATION OF PENNSYLVANIA.

BALL-FINISHING MACHINE.

1,223,087.

Specification of Letters Patent. Patented Apr. 17, 1917.

Application filed February 9, 1916. Serial No. 77,131.

To all whom it may concern:

Be it known that I, FRANK MAYHEW, a citizen of the United States, and resident of Philadelphia, county of Philadelphia, and 5 State of Pennsylvania, have invented new and useful Improvements in Ball-Finishing Machines, of which the following is a specification.

The object of the invention is to provide 10 a machine in which a number of balls can be simultaneously ground, polished or burnished so as to give to the exterior of the balls operated upon a smooth and uniform exterior.

15 The invention is preferably realized by pressing the balls between relatively rotating heads, each head having a plurality of circular ball-receiving-grooves or raceways. The grooves in one of said heads—which 20 head may be referred to as a resisting head or ball-supporting ring or head—are arranged concentric with each other. The opposing head—which may be referred to as a pressing head—has a plurality of concentric 25 members each having a ball-receiving-groove or raceway that is opposed to one of the grooves or raceways in the resisting head.

The concentric members of the pressing head may be referred to as pressing rings or 30 members and they are free to float or move relative to each other whereby each pressing ring can adapt itself to the work—that is, to the balls—upon which it is operating. The operating ends of the opposed heads are 35 made of metal, preferably cast iron, and the grooves therein are of the proper cross sectional configuration to fit the balls which are to be operated upon in the machine. When the balls are merely to be given a 40 high polish they are pressed between said relatively rotating heads and a bath of clear oil is supplied to them. If a slight grinding action is desired a certain amount of emery or like abrasive substance is mixed in the oil.

45 As showing certain specific embodiments of machines in which the invention may be realized reference is made to the drawings forming a part of this specification and in which drawings,

50 Figures 1 and 2 are respectively side and front elevations of a grinding, polishing or

burnishing machine in which the invention is realized. The lower portion of the standard for the machine shown in these figures is broken off.

55 Fig. 3 is a vertical sectional view showing the arrangement of the opposing heads. This is a view as taken on the broken line 3—3 in Fig. 4.

Fig. 4 is a plan view of the parts shown in 60 Fig. 3.

Fig. 5 is a vertical sectional view showing another form of opposing heads. This figure is a view as taken on the broken line 5—5 in Fig. 6.

65 Fig. 6 is a plan view of the heads illustrated in Fig. 5.

Fig. 7 is a partial vertical sectional view taken on the line 7—7 in Fig. 6 looking in the direction of the arrows.

70 A designates the frame of the machine which frame comprises a standard B, a horizontally extending table C and an upright D. The machine is shown as being provided with opposing heads E which are the same 75 as those illustrated in Figs. 3 and 4, but it will be understood that the heads shown in Figs. 5 to 7 could be employed in place of those in position in the machine. The lower head F of this set of opposing heads 80 E may be referred to as a resisting head or as a ball-supporting ring or head. The upper head G may be referred to as a pressing head and it comprises annular concentric pressing rings or members H, H¹ and 85 H². It also comprises as a part thereof a yoke K through which bolts L, L¹ and L² pass whereby when the yoke is raised in a manner hereinafter described the rings or members H, H¹ and H² will also be raised. 90 When in operation three series of balls, in a device having three rings, are located in the respective ball-receiving grooved portions or raceways N, N¹, N². These grooves are all circular and in cross section are of the proper size and shape to fit the balls which are to be operated upon in the grooves. The balls, when in these grooved portions N, N¹, N², enter respectively the corresponding ball-receiving grooved portions or raceways 95 O, O¹, O² that are located at the underside of the rings H, H¹ and H² when the latter

rest upon the balls. When the rings are resting upon the balls in the manner just referred to they are rotated through the agency of the yoke engaging buffing washers ⁵ P P¹ P² that respectively surround the screw-studs Q Q¹ Q². The openings M M¹ M² in the yoke K through which the bolts L L¹ L² pass are substantially larger than the bolts whereby a certain freedom of ¹⁰ movement of the several rings relative to each other is permissible during the time the yoke is serving to drive the pressing rings H H¹ and H². This yoke K is carried on the lower end of a vertically extending driving ¹⁵ spindle R; this driving spindle R is in turn driven in any suitable manner as through the agency of the tight and loose pulleys S and S'—the shaft T carrying the same—and the bevel gears U and V. The spindle ²⁰ R is slidable through the gear and can be raised by means of a sleeve W having a rack W', gear mechanism X which engages said rack and a handle Y. The opposing heads illustrated in Figs. 5, 6 and 7 comprise ²⁵ the lower supporting ring or head FF and two concentric pressing members HH and HH¹. The disk member KK corresponds in function to the yoke K; it and also the member HH¹ may be considered to constitute ³⁰ the inner pressing member of the upper head. This disk member KK also serves the same function as that of the yoke K shown in Fig. 3, to both drive the outer ring HH, as through the agency of the plate ³⁵ LL, and the bushed-screw PP. The plate LL and two other plates, to wit, plates LL¹, which plates are all arranged about 120° apart, serve as means whereby the disk member KK when raised can be relied upon to ⁴⁰ also raise the outer ring HH¹. The ring HH¹ is provided with rods MM as a means for securing the ring HH¹ to the disk member KK so that when the disk KK is raised the ring HH¹ will also be raised. In order ⁴⁵ that the ring HH¹ may be free to float relative to the disk KK, when in operation, a clearance is provided in the openings through which the rods MM pass and when it is desired to permit this movement the ⁵⁰ nuts NN on the rods are loosened.

The several concentric rings H H¹ H² are preferably made of cast iron and they are comparatively large whereby when in operation a considerable pressure will be exerted ⁵⁵ against the balls which are being operated upon in the machine. For this reason each individual ring or concentric member may be referred to as an independent pressing ring which is free to float or adjust itself relative to the other ring or concentric member in the head so as to accommodate itself to the work being operated upon.

Similar remarks apply to the construction shown in Figs. 5 to 7. In the last mentioned

figures the member HH is a comparatively heavy member; as to the member HH¹ its effective weight is increased by the weight of the disk member KK and also by the unbalanced weight of the spindle R to which the disk member KK is secured. If sufficient free radial movement were provided in the spindle the member HH¹ could be rigidly secured to the disk KK or could even be made integral with and a part of the disk KK. In such a construction the inner and outer members would be free to move relative to each other when in operation so as to accommodate themselves to the work. As the several grooves at the upper surface of the supporting ring or resisting head are concentric with each other only a very limited movement is required between the different concentric pressing rings, but a limited movement has been found essential where it is desired to obtain a fine product. ⁸⁰ The lower supporting ring or resisting head is preferably slidably mounted on the horizontally extending table C.

When the machine is to be emptied and recharged the free end of the handle Y is pulled down thus effecting a raising of the upper head G. The amount of movement obtained is sufficient to permit the supporting ring or resisting head, together with the several sets of balls that have been operated upon, to be removed from underneath the pressing head by sliding the supporting ring or head horizontally on the table C. After the balls which have been operated upon are removed a new set of balls is placed in each of the receiving grooves or raceways at the top of the resisting head, the head is slid in place underneath the pressing head, the latter is then lowered and revolved for a sufficient period to effect the grinding, polishing or burnishing operation, as may be desired.

As previously indicated, if a grinding operation is desired oil mixed with an abrasive is introduced in the ball-receiving grooves, whereas if only a polishing or burnishing operation is desired a clear, clean oil is supplied to the space between the heads.

The improvements herein set forth are not limited to the precise construction and arrangement shown and described for they may be embodied in various forms and modification without departing from the spirit and scope of the invention.

What I claim is:

1. A machine of the class described comprising in combination opposed heads between which a relative rotation takes place, each head having a plurality of concentric ball-receiving grooves, one of said heads having concentric pressing rings or members which are free to float or move relative to each other while in operative engagement with

balls that are between said heads and in the grooves thereof.

2. A machine of the class described comprising in combination opposing heads each having a plurality of concentric ball-receiving grooves or raceways, and means for imparting relative rotation between said opposing heads, one of said heads comprising a plurality of pressing rings which can move relative to each other when they are in engagement with the balls being operated upon.

3. A machine of the class described comprising in combination a frame, a supporting head mounted upon said frame so that it can slide longitudinally thereupon, said head having upon its upper surface a plurality of concentric ball-receiving grooves or raceways, a vertically extending spindle carried in said frame, means for rotating said spindle, and a plurality of concentric upper rings or pressing members each of which has on its under surface a groove for receiving therein the balls which are in one of the grooves in said supporting ring, there being provided means between the upper rings or members and the shaft whereby said upper rings will be driven from said shaft, the construction being such that the upper rings are free to adjust themselves relative to each other and relative to the supporting head.

4. A machine of the class described comprising in combination a frame having a horizontally extending table, a supporting ring or member slidably mounted upon said table, said supporting ring or member having upon its upper surface a plurality of concentric circular grooves, a plurality of pressing rings located above said supporting ring, each pressing ring having on its underside a circular grooved portion which is opposed to one of the grooved portions in the supporting ring, a shaft mounted in said machine, and means whereby said shaft will rotate said pressing rings which are free to move relative to each other so as to accommodate themselves to do the work when they are in operating engagement therewith, the machine also being provided with means whereby said pressing rings can be lifted away from the supporting ring in order to permit the latter ring to be slid horizontally on the table from operative position.

5. A machine of the class described comprising in combination a frame, a ball supporting member carried on said frame, said ball supporting member having on its upper surface concentric ball-receiving grooves a plurality of pressing members arranged above the supporting member each pressing member having on its underside a ball-receiving groove that is opposed to a ball-

receiving groove in the supporting member, a shaft carried in said frame, means for rotating said shaft, a yoke on the lower end of said shaft and means between said yoke and said pressing members whereby they will be rotated relative to the supporting member, the construction of said means being such that the pressing members are free to float or move relative to each other when they are in operative engagement with the balls being operated upon.

6. A machine of the class described comprising in combination a frame, a lower supporting member having a plurality of concentric ball-receiving grooved portions at its upper surface, a plurality of floating upper rings or members each having on its underside a ball-receiving grooved portion that is opposed to one of the ball-receiving grooved portions on the lower member, a shaft, and connections between the shaft and said floating rings or members whereby the latter will be driven from said shaft, means for raising and lowering said shaft the connecting means between said shaft and said rings being such that with the raising of the shaft the floating rings will be raised.

7. A machine of the class described comprising in combination opposed heads and means for causing relative rotation between said heads, one of said heads comprising a plurality of concentric ball-receiving grooves or raceways and the other of said heads comprising a corresponding number of ball-receiving grooves or raceways, one of said heads also comprising a plurality of rings or members which are free to adjust themselves relative to each other in order to accommodate themselves to the work being operated upon, the machine parts being constructed and arranged so that balls in the grooves between said heads will be pressed between said heads as the relative rotation of the heads take place.

8. A machine of the class described comprising in combination a resisting head, a pressing head opposed to the resisting head which heads are provided with concentric grooved portions for receiving therein balls when being operated upon by the heads, means for rotating the pressing head relative to the resisting head one of said heads comprising a plurality of rings or concentric members each of which members has upon its operative surface one of the grooved portions referred to said members being free to move relative to each other whereby they can accommodate themselves to the work being operated upon.

9. A machine of the class described comprising a resisting head, a pressing head and means for causing relative rotation between said heads, said pressing head comprising a plurality of concentric members which are

- free to adjust themselves relative to each other the resisting head having on its face adjacent to the pressing head a plurality of concentric circular grooved portions or raceways, each of the concentric members of the pressing head having upon the face which is opposite to the resisting head a circular grooved portion or raceway that is arranged to receive therein balls that are in one of the sets of grooves on the resisting head.
10. A machine of the class described comprising in combination a frame, a ball supporting member or resisting ring carried on said frame, an upper pressing head which comprises an inner pressing member and an outer annular pressing member, a vertical shaft mounted in said frame, means for rotating said shaft and means for raising said shaft, the inner and outer members of the pressing head being connected to each other and to the shaft in such a way that when the shaft is rotated said inner and outer members will be rotated and so that when the shaft is raised said inner and outer members will be raised from operative position, the supporting member having upon its upper face a plurality of concentric ball-receiving grooved portions or raceways the inner and outer pressing members each having on its under-surface a grooved portion or raceway which receives therein a set of balls which are in one of the corresponding grooved portions or raceways on said upper face.
20. A machine of the class described comprising in combination a frame having a horizontally extending table, a resisting ring slidably mounted upon said table and provided on its upper surface with concentric ball-receiving grooved portions or raceways, a pressing head comprising concentric inner and outer members having ball-receiving grooved portions or raceways which are opposed to the ball-receiving portions or raceways on the resisting ring when the latter is in position under the pressing head, a shaft operatively connected to said head for rotating the members thereof, means for rotating said shaft, and means for raising said shaft whereby said pressing head will be lifted away from operative position above the resisting ring the inner and outer members of said pressing head being free to float relative to each other as they are pressed against the balls while the latter are being operated upon.
30. A machine of the class described comprising in combination a frame having a horizontally extending table, a resisting ring slidably mounted upon said table, which resisting ring has upon its upper surface a plurality of concentric ball-receiving grooved portions or raceways, a head arranged above the resisting ring, which head comprises a plurality of annular 65 concentric pressing rings or members each of which pressing rings has a ball-receiving grooved portion or raceway which is opposite to a grooved portion in the resisting ring, a vertically extending shaft mounted in said frame, means for rotating said shaft, means for raising and lowering said shaft, a yoke on the lower end of said shaft, and means between said yoke and said pressing rings whereby said rings will be rotated by 70 said shaft but will also be free to move relative to each other so as to accommodate themselves to the work being operated upon, there also being provided between the yoke and rings means whereby when the shaft 75 with the yoke thereupon is raised the pressing rings will also be raised.
40. A machine of the class described comprising in combination a supporting member having upon its upper surface a plurality of circular concentric raceways serving as ball-receiving grooves, a pressing head arranged above the supporting member, a shaft for rotating said pressing head said pressing head comprising an inner pressing member having a ball-receiving groove on its under-surface and an outer ring which 80 also has a ball-receiving groove on its under-surface, the outer ring being operatively connected to said inner pressing member whereby as the shaft is raised the inner and outer pressing members will also be raised.
50. A machine of the class described comprising in combination a frame, a ball supporting member or ring carried on said frame, an upper pressing head which comprises an inner pressing member and an outer annular pressing member, a vertical shaft mounted in said frame, means for rotating said shaft, and means for raising said shaft, the inner and outer members of the pressing head being connected to each other and to the shaft in such a way that when the shaft is rotated said inner and outer members will be rotated so that they can accommodate or adjust themselves relative to each other and so that when the shaft is raised said inner and outer members will be raised from operative position, the supporting member having upon its upper face a plurality of concentric ball-receiving 90 grooved portions or raceways the inner and outer pressing members each having on its under-surface a grooved portion or raceway which receives therein a set of balls which are in one of the corresponding grooves or raceways on said upper face.
60. A machine of the class described comprising in combination a frame having a horizontally extending table, a resisting ring slidably mounted upon said table, which resisting ring has upon its upper surface a plurality of concentric ball-receiving grooved portions or raceways, a head arranged above the resisting ring,
110. A machine of the class described comprising in combination a supporting member having upon its upper surface a plurality of circular concentric raceways serving as ball receiving grooves, a pressing 115
- 120.

head arranged above the supporting member, a shaft for rotating said pressing head said pressing head comprising an inner pressing member having a ball-receiving groove on its under surface and an outer ring which also has a ball-receiving groove on its under surface, the outer ring being operatively connected to said inner pressing member whereby as the shaft is raised the inner and outer pressing members will also

be raised, the constriction being such that the rings are free to move relative to each other whereby they can accommodate themselves to the work being operated upon.

This specification signed and witnessed 15 this 7th day of February, A. D. 1916.

FRANK MAYHEW.
